Primary Examiner — Selina Sikder*(74) Attorney, Agent, or Firm* — Nixon Peabody LLP(57) **CLAIM**

The ornamental design for hand control, as shown and described.

DESCRIPTION

FIG. 1 is a front perspective view of hand control showing my new design;

FIG. 2 is a rear perspective view thereof;

FIG. 3 is a first side view thereof;

FIG. 4 is a front view thereof;

FIG. 5 is a second side view thereof;

FIG. 6 is a rear view thereof;

FIG. 7 is a top view thereof; and,

FIG. 8 is a bottom view thereof.

The broken lines in all the figures are for the purpose of illustrating portions of the hand control and other indicia, which represent unclaimed subject matter and form no part of the claimed design. The hand control shown in the figures can be used for controlling, for example, a hoist.
